US00D841816S

(12) **United States Design Patent** (10) **Patent No.:** **US D841,816 S**
Min et al. (45) **Date of Patent:** **** Feb. 26, 2019**

(54) **WIRELESS BIO SIGNAL MEASURING DEVICE**

(71) Applicant: **SOSO Co., Ltd**, Daegu (KR)

(72) Inventors: **Dong-Bin Min**, Gimpo-si (KR); **Jae-Yong Lee**, Seoul (KR); **Dae-Sik Keum**, Seoul (KR)

(73) Assignee: **SOSO CO., LTD.**, Daegu (KR)

(**) Term: **15 Years**

(21) Appl. No.: **29/596,141**

(22) Filed: **Mar. 6, 2017**

(30) **Foreign Application Priority Data**

Dec. 1, 2016 (KR) 30-2016-0058152

(51) **LOC (11) Cl.** **24-02**

(52) **U.S. Cl.**

USPC **D24/173**

(58) **Field of Classification Search**

USPC ... D10/30-32, 38, 40, 41, 46, 70, 79, 106.5, D10/106.6, 106.92, 106.94, 114.6, 123, D10/125, 126, 128, 131; D11/1-4, 93, D11/94; D14/138, 144, 641, 644, 658, D14/458; D24/167, 169, 186, 187, 173

CPC H04R 1/105; H04R 2201/107; H04R 2420/07; H04M 1/6066

(57) **CLAIM**

The ornamental design for a “wireless bio signal measuring device”, as shown and described.

DESCRIPTION

FIG. 1 is a front perspective view of a wireless bio signal measuring device showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

The broken lines show portions of a wireless bio signal measuring device that form no part of the claimed design.

1 Claim, 8 Drawing Sheets
